A. ALDRICH

PAPER MAKING MACHINE

Filed Oct. 18, 1922

Witness:

W. Aldrich

Inventor:

Alonzo Aldrich

By *A. Wm. Peffell, Atty.*

UNITED STATES PATENT OFFICE.

ALONZO ALDRICH, OF BELOIT, WISCONSIN.

PAPER-MAKING MACHINE.

Application filed October 18, 1922. Serial No. 595,255.

To all whom it may concern:

Be it known that I, ALONZO ALDRICH, a citizen of the United States, residing at Beloit, in the county of Rock and State of Wisconsin, have invented a certain new and useful Improvement in Paper-Making Machines, of which the following is a full, clear, concise, and exact description, reference being had to the accompanying drawings, forming a part of this specification.

My invention relates to paper making machines, particularly to the Fourdrinier variety.

The principal object of the invention is to produce or secure a good formation in the paper made by the machine.

Another object of the invention is to secure simple and effective means for obtaining this result.

20 In the accompanying drawings Fig. 1 is a side elevation of the brest roll end of a Fourdrinier machine embodying my present invention;

Fig. 2 is an end view of one of the table rolls of the same;

Referring to the drawings, and particularly to Figs. 1 and 2, I show a table 1 having a brest roll 2 and table rolls 3—3 with wire 4 passing over the same.

The table rolls 3—3 are of improved construction in order to secure certain desirable results, as will be explained. In the form of roll shown, see Fig. 2, the roll 3 is mounted eccentrically on its shaft, so that the roll as a whole will vibrate the wire, and thereby agitate the pulp and give the paper a good formation. Other constructions may be used for securing the desired result.

It will be understood that changes and modifications may be made without departing from the spirit of the invention.

What I claim is:

In a Fourdrinier machine, the combination with the wire of table rolls mounted eccentrically on their axes.

45 In witness whereof, I hereunto subscribe my name this 18th day of September, A. D., 1922.

ALONZO ALDRICH.
